PREHEATER

Fritz Graetz, Berlin, Germany

Application December 17, 1935, Serial No. 54,826
In Germany August 2, 1935

5 Claims. (Cl. 299—140)

This invention relates to a preheater for lighting and heating apparatus fed with fuel subjected to air pressure.

Preheaters for the vaporizer of such apparatus, 5 in which fuel and air are jointly drawn from a container and atomized so as to produce an inflammable and combustible mixture, are known already, and the object of the invention is to improve preheaters of this type, particularly as regards protection against wind, and simultaneously 10 to provide for convenient cleaning of the nozzles.

It has been proposed to employ flat rotary valves 15 as stop members for such preheaters, but the construction is so arranged that the rotary valve acting from the outside covers the outlet nozzle when in locking position, which makes it impossible to clean this nozzle when it is inoperative and the apparatus is under pressure. Furthermore, in these known preheaters no provision is made for preventing, or rendering difficult at least, blowing 20 out of the flame, for instance by the wind, when the device is used in the open air.

The invention attains both objects stated, which 25 at first sight appear to have little in common, by one and the same means, according to which the rotary valve serving for simultaneously and separately shutting off fuel and air is made the carrier of the atomizer and flame tube or guard.

By way of example, the invention is illustrated 30 in the accompanying drawing, which shows a preheater applied to an incandescent storm lantern and in which Figure 1 is a vertical section on the line 1—1, of Fig. 2, of a lantern and preheater; Fig. 2 is a horizontal section on the line 35 2—2, of Fig. 1; Fig. 3, a top view of the rotary slide valve and passages; and Fig. 4, a section of the leaf spring exerting pressure upon the valve.

Referring to the drawing, the pressure resisting 40 container 1 of an incandescent storm lantern of known type is provided with an air pump 2 and a 45 filler cap 3, and carries the lower part 4 of the lantern housing. The vaporizer 5 is eccentrically secured to the container 1 and fitted with a stop valve 6. Other parts of the lantern proper are not shown, as they do not affect the invention.

A body member 8 is inserted in an inclined 50 screw connection 7 on the container 1 and is provided with two conduits 9, 10, the conduit 9 accommodating a pipe 27 communicating with the air space of the container 1, and the conduit 10 accommodating a fuel supply pipe 11 which reaches almost to the bottom of the container. The body member 8 is fitted with a plate 12, preferably made of petroleum-proof rubber-like material, through which the pipe 11 extends nearly

up to the slide face. The pipe 27, inserted in the conduit 9, extends through the plate 12 almost to the top of the latter. These pipes act as passages and serve not only for preventing swelling of the plate material and closing of the conduits, but they further stop the plate 12 from participating in the movement of the upper part of the preheater, which will be described hereafter.

The atomizer comprises a rotary member 13, 10 an air nozzle 14 and a mixing nozzle 15. The member 13 is traversed by conduits 16, 17 which lead, respectively, to the mixing space and the air nozzle, so that when the slide is opened the conduit 10 will communicate with the conduit 16 and the conduit 9 with the conduit 17. The atomizer body 13 has a lower flange 18 subjected to the pressure of the annular leaf spring 19 which is held in position by the cap nut 20, so that the slide faces, relatively movable to one another, are pressed together tightly yet so as to be slightly movable.

The rotary slide thus formed is operated by the lever 21. The flange 18 possesses a recess 22 whose end faces co-operate with a stud 23 in the body member 8 to limit the motion of the slide. 25 A flame tube or guard 24, attached to the mixing nozzle 15, is provided on its circumference with an igniting and cleaning hole 25 on a level with a recess 26 in the lower part of the lantern housing. 30

The preheater described functions as follows:

The container 1 is half filled with fuel. When the filler cap 3, the vaporizer valve 6 and the rotary slide of the preheater are closed, air is introduced into the container 1 by means of the pump 2 until the pressure is somewhat in excess of the operating pressure. The preheater is then opened by turning the lever 21 in the direction of the arrow A up to the stop. During opening, the conduits 9 and 10 will be brought first into communication, since the air pipe has an advanced opening, as indicated in Fig. 3, so that only air flows out. Progressive turning of the slide then brings the conduits 16 and 17 likewise into communication, and fuel will be drawn in by the suction of the air jet. The not exactly simultaneous opening of the conduits due to the advanced air opening provided by the invention affords the considerable advantage that a current of pure air always passes first through both nozzles and cleans them. The time during which this takes place, however, is not determined by the accomplishment of the suction or injector effect of the air current, but is entirely optional with the user 50 who may continue to pass air only through the 55

nozzles until the sound of the discharge indicates that they are both clean and fully opened.

In the end position of the lever 21 in which the conduits 16 and 17 are completely obturated, and one edge of the recess in flange 18 abuts the stud 23, the apertures 25 and 26 are in complete registration one with the other.

During opening of the preheater conduits the flame tube 24 is simultaneously brought out of the position at which the recesses 25, 26 register completely one with the other into a position where they only partly coincide and just enough space is available for allowing a lighted match to reach the issuing jet of the combustible mixture. This represents the other end position of lever 21 in which the stud 23 contacts with the other edge of the recess in flange 18.

In view of the fact that when the apertures 25 and 26 are in complete registration when no fuel or air is feeding through the preheater, it is therefore possible conveniently to clean both nozzles when the preheater is inoperative, even if the apparatus is under pressure, whereas, on the other hand, when the preheater is in operation, the igniting hole will be accessible laterally from the exterior of the apparatus only through a comparatively narrow slit so that the issuing jet of the mixture cannot be rectilinearly struck by a wind stream and blown out.

30 As soon as the vaporizer 5 is sufficiently warmed by the flame of the preheater, the valve 6 is opened and the mixture emerging from the burner, not shown, is ignited by the flame of the preheater. The lever 21 is then turned in the direction of the arrow Z and thereby brought into closing position, and the main flame continues to burn alone. The pressure at which the apparatus then works should be the normal operating pressure, as part of the air supplied by the pump 40 has been used for atomizing the fuel in the preheater.

I claim:—

1. A multiple valve comprising a lower member adapted to be attached to a source of supply, said lower member having passages, an upper member rotatably mounted on said lower member, an air nozzle and a mixing nozzle mounted on said upper member and rotatable therewith, one of said nozzles being located within said upper member and said other nozzle, passages in said upper member communicating with said nozzles and a wind guard mounted on said upper member and rotatable therewith.

2. A multiple valve comprising a lower member adapted to be attached to a source of supply, said lower member having passages, a pipe in each of said passages, an upper member rotatably mounted on said lower member, an air nozzle and a mixing nozzle mounted on said upper member and rotatable therewith, one of said nozzles being

located within said upper member and said other nozzle, passages in said upper member communicating with said nozzles and a wind guard mounted on said upper member and rotatable therewith.

3. A multiple valve comprising a lower member adapted to be attached to a source of supply, said lower member having passages, an upper member rotatably mounted on said lower member, an air nozzle and a mixing nozzle mounted on said upper member and rotatable therewith, one of said nozzles being located within said upper member and said other nozzle, passages in said upper member communicating with said nozzles and a wind guard mounted on said upper member and rotatable therewith, said wind guard having an aperture, a lantern housing having an aperture adapted to align with the aperture of said wind guard when the latter has been rotated to a certain position.

4. A multiple valve comprising a lower member adapted to be attached to a source of supply, said lower member having passages, an upper member rotatably mounted on said lower member, an air nozzle and a mixing nozzle mounted on said upper member and rotatable therewith, one of said nozzles being located within said upper member and said other nozzle, passages in said upper member communicating with said nozzles and a wind guard mounted on said upper member and rotatable therewith, said wind guard having an aperture, a lantern housing having an aperture adapted to align with the aperture of said wind guard when the latter has been rotated to a certain position, and means whereby one of said 35 passageways of said upper member becomes aligned with one of the passages of said lower member in advance of the alignment of the upper passage of said upper member and the other passage of said lower member, and a wind guard mounted on said upper member and rotatable 40 therewith.

5. A multiple valve comprising a lower member adapted to be attached to a source of supply, said lower member having passages, a pipe in each of said passages, an upper member rotatably mounted on said lower member, an air nozzle and a mixing nozzle mounted on said upper member and rotatable therewith, one of said nozzles being located within said upper member and said other nozzle, passages in said upper member communicating with said nozzles and a wind guard mounted on said upper member and rotatable therewith, said wind guard having an aperture, a lantern housing having an aperture, said apertures being adapted to be brought into alignment when the wind guard has been rotated to a certain position.

FRITZ GRAFTZ.
